FIG. 3

FIG. 4

FIG. 5

Figure 5 is a grid of numbers. The columns are labeled with letters A through Y at the top, and the rows are numbered 01 through 00 on the left. A small number '16' is written above the first column. A small number '11' is written to the left of the first row. A small number '17' is written above the first cell of the second column. A small number '12' is written to the left of the second row. The grid contains the following data:

A	B	C	D	E	F	G	H	J	K	L	M	N	O	P	Q	R	S	T	U	V	W	X	Y	
01	02	03	04	05	06	07	08	09	10	11	12	13	14	15	16	17	18	19	20	21	22	23	24	25
26	27	28	29	30	31	32	33	34	35	36	37	38	39	40	41	42	43	44	45	46	47	48	49	50
51	52	53	54	55	56	57	58	59	60	61	62	63	64	65	66	67	68	69	70	71	72	73	74	75

WILLIAM N. HOWARD, OF LOS ANGELES, CALIFORNIA.

INDEX DEVICE.

Application filed January 30, 1926. Serial No. 84,858.

This invention relates to a system and devices for maintaining number bearing cards in proper order and for enabling quick removal of a certain card when desired.

5 The general object of the invention is to provide an improved card file which will enable consecutively numbered cards to be readily classified or separated.

10 One of the specific objects of the invention is to provide a file of consecutively numbered cards wherein the individual cards each have a signal comprising a letter thereon and wherein the like signals are disposed back of each other in a straight 15 line.

Another object of the invention is to provide a file comprising sets of numbered cards having visible signals wherein cards bearing numbers differing by multiples of 20 twenty-five are placed with the signals in a straight line back of each other.

25 Another object of the invention is to provide a consecutively numbered card file comprising a plurality of sets of twenty five cards each wherein the upper portion of each card is notched and is provided with a signal and wherein the signal is a letter.

30 Other objects of the invention will be apparent from the following description taken in connection with the accompanying drawings wherein:

Fig. 1 is a fragmentary front elevation of a file embodying the features of my invention;

35 Fig. 2 is a view similar to Fig. 1 showing the cards of a hundred group whose signal is E;

Fig. 3 is a plan view showing a single card;

40 Fig. 4 is an end view showing a plurality of cards; and

Fig. 5 is a chart showing the numbers of a hundred group used with each signal letter.

45 As stated, the general object of the invention is to provide an improved alphabetically signalled, numerically arranged card file. The cards embodying the features of my invention, which will be presently described, 50 enable an operator to readily file numerically designated cards. With my invention any desired cards may be quickly and readily withdrawn from a file and it also visual-

ly indicates when any of the cards have been removed or are improperly filed.

55 Referring to the drawing by reference characters, I have shown a section of one hundred cards of a card index at 10.

Each such section comprises a plurality of cards which may be numbered consecutively by numbers preferably placed adjacent the top of each card as at 11. The cards are shown as arranged in sets of twenty-five as shown at 12, although other arrangement may be made without departing 60 from the spirit of my invention.

65 The cards are adapted for a number of different purposes as will be obvious, and among them I may mention the recording of 70 automobile license plate numbers and the recording of information useful in the business of abstracting titles. In Fig. 3 the card shown is provided with information 75 relating to a real estate transfer. The cards may have blank forms printed thereon if desired. In fact the use to which the cards are put forms no part of my present invention which relates to a novel system for filing the cards and for distinguishing the 80 individual cards in a file.

85 Each of the record cards of the group 10 is shown as provided with a notched portion 15 and adjacent this notched portion I show a signal at 16. Between successive groups of one hundred cards I may insert a numbered guide card 17 if desired. This guide 90 may project above the cards as shown.

95 The file shown in the drawings includes cards numbered consecutively from 1 to 100. The first card 1 is provided with a signal 20 shown at 18 in Fig. 1 as the letter A. The second card which is numbered 2 is provided with a signal B which is shown at 19 (Fig. 1) as arranged slightly to the right of the signal 18. The third card is numbered 3 and is provided with the signal C. The next card numbered 4 has the signal D as shown in Fig. 1 and so on.

100 The arrangement described is continued until a complete set of twenty-five cards is provided. The purpose of this arrangement is so that four sets will provide a group comprising an even hundred cards.

105 As there are twenty-six letters in the alphabet, with my use of letters as signals, it becomes necessary that the use of one letter

as a signal be omitted. I now prefer to omit the letter I, although of course it will be understood that any other letter may be omitted if desired. It will also be understood that instead of using the letters described I may use arbitrary arrangements of letters or groups of letters as desired.

In each group of one hundred cards there will be four cards bearing the same signal.

10 These cards bearing the same signal will bear numbers thereon which differ from each other by multiples of twenty-five. For instance, in Fig. 2 I show cards numbered 5, 30, 55 and 80. Each of these cards bears the signal letter E shown at 16, and it will be noted that the numbers 5, 30, 55 and 80, on these cards differ from each other by twenty-five and that each card in the set differs from all the other cards in the set

15 by numbers which are a multiple of twenty-five. For instance, 5 differs from 30 by 25, while 5 differs from 80 by 75; both multiples of twenty-five.

An experienced operator very quickly operates these cards to select or file the desired number. For instance, the operator will quickly learn that the card numbered 30 is the second E card in the set. In a similar manner the operator will learn that the card numbered 91 is the last Q card in the set.

However, in order to facilitate use of the cards either by a novice or by one who uses them infrequently, I prefer to print upon the cards numbers shown at 20 in Fig. 2. These numbers may preferably appear near the signal 16 and the numbers are those which correspond to those present in the tens and units columns of the cards bearing the same signal.

40 I prefer to distinguish the signals E, K, P, U, and Z which are the signals for the cards whose numbers are even fives and even tens since with a distinguishing mark the operator can very quickly pick out the desired cards by first referring to the distinguished part. I now prefer to color the overlapping portions of the cards bearing the signals E, K, P, U, and Z for this purpose.

The cards in each set are preferably of the same size and they may be arranged with the sets stepped, as shown, or they may be arranged with the top of the signals all in the same plane.

From the foregoing description it will be apparent that I have provided an improved signal and grouping system for numerically numbered cards which is extremely simple, which will enable a card to be readily removed or replaced in the proper position and wherein the absence of a card will be readily detected by the absence of the signal.

Having thus described my invention, I claim:

1. In a filing and indexing device, a plurality of cards each having an identifying

number thereon, each of said cards also having a signal thereon, said signal being a letter, all cards which have the same signal having identifying numbers thereon differing by multiples of 25.

2. In a filing and indexing device, a plurality of cards consecutively numbered, each of said cards having a signal thereon, said signal being a letter, all cards which have the same signal having numbers thereon differing by multiples of twenty-five, said cards being arranged with the same signals disposed in straight lines.

3. In a filing and indexing device, a plurality of cards bearing consecutive numbers, said cards each having a normally visible signal displayed thereon, the signal visible on each card being a letter, the cards bearing numbers having certain arbitrarily chosen characteristics having the same letter as a signal.

4. A set of cards numbered consecutively, said cards each having a visible signal thereon, the cards whose numbers differ by multiples of twenty-five having the same signal visible thereon.

5. A set of cards numbered consecutively, said cards being arranged in multiple sets of twenty-five with a letter displayed on each card as a signal and with the cards which bear numbers which are multiples of twenty-five having their signals disposed at the right for the purpose of indicating the different sets, the signals being arranged in straight lines with the same signal displayed in each line.

6. A set of cards numbered consecutively, said cards being arranged in multiple sets of twenty-five with a letter displayed on each card as a signal and with the cards which bear numbers which are multiples of twenty-five having their signals disposed at the right for the purpose of indicating the different sets, the signals being arranged in straight lines with the same signal displayed in each line, the cards whose signals are arranged in any one line having numbers thereon differing from each other successively by twenty-five.

7. A set of consecutively numbered cards, said set comprising a plurality of groups of twenty-five cards each, said cards being notched at one corner and having a letter visible thereon as a signal, the cards whose numbers end in 01, 26, 51, and 76 having the letter A as a signal, the cards whose numbers end in 02, 27, 52 and 77 having the letter B as a signal, with the arrangement repeated in order and with the letter I omitted, said signals which are the same being arranged in straight lines back of each other.

In testimony whereof, I hereunto affix my signature.

WILLIAM N. HOWARD.
